Walter Bryant. Design for ornament.
Patented 13th August 1873.

DESIGN 305

Fig. 1

Fig. 2

Des. 305

Walter Bryant of Boston Mass
Letters Patent No 305. Dated 13. August 1850

The Schedule referred to in these Letters Patent and making part of the same

To all Persons to whom these Presents shall come:

Be it known that

I Walter Bryant of Boston, in the County of Suffolk, and State of Massachusetts have invented or produced a new and useful design for a cast iron bracket, to be screwed to walls, for supporting marble tablets &c. and I do hereby declare, that the said new design is fully described and represented in the following Specification and accompanying drawings, to which reference is hereinafter made.

Of the drawings Fig. 1 is a side elevation of the bracket, and Fig. 2 is a section taken in the plane of the line A B.
Fig. 1.

Both sides of the brackets are alike, and it is confined to the wall, by screwing through the vertical plate aa, the horizontal plate, bb, supporting the tablet; the said two plates of course being at right angles to each other.

My new design consists of the large Grecian scroll c c c, terminating at each end in the volute d d, having a single leaf pendent from its centre, and an enriched double leaf f. pendent from its volute, said centre

2

Des. 305

scroll being connected to the plates a & a & b & b , by the smaller Grecian scrolls g & g , h & h , i & i , & k & k , which are joined by the fluted ties l , l , l , l , as shown in the drawings Fig. 1. Fig. 2 shows the sectional contour of the scrolls.

Having thus described my new design, I shall state my claim as follows:

What I claim as my invention or production, and desire to have secured to me by Letters Patent is the combination of the central Grecian scroll, with its heraldic leaves, with the several smaller Grecian scrolls, & fluted ties, herein above enumerated, & represented in the drawings, the whole forming a connection between the vertical and horizontal plates of a cast iron bracket.

Witnesses.
